Elizabeth Thorpe INVENTOR.

BY

Shepherd & Campbell ATTORNEY.

UNITED STATES PATENT OFFICE.

ELIZABETH THORPE, OF CLEARWATER, FLORIDA.

GARMENT-MARKER AND SKIRT-GAGE.

Specification of Letters Patent. Patented Mar. 22, 1921.

1,372,107.

Application filed July 3, 1920. Serial No. 393,975.

To all whom it may concern:

Be it known that I, ELIZABETH THORPE, a citizen of the United States, residing at Clearwater, in the county of Pinellas and

5 State of Florida, have invented certain new and useful Improvements in Garment-Markers and Skirt-Gages, of which the following is a specification, reference being had therein to the accompanying drawings.

10 This invention relates to a combined garment marker and skirt gage and it has for its object to provide an improved article of this nature possessing points of superiority and advantage over any known device. 15 These points of superiority and advantage will be fully set forth in the detailed description which now follows.

In the accompanying drawing:

Figure 1 is a perspective view illustrating 20 the device attached to the edge of a door in position to serve as a garment marker;

Fig. 2 is a detail view of a pinning wire hereinafter described; and

Fig. 3 is a side elevation of the device 25 illustrating its use as a skirt gage.

Like numerals designate corresponding parts in all of the figures of the drawing.

Referring to the drawing it will be seen that the particular form of the device which 30 I have chosen to illustrate the invention comprises a U shaped member 6 having rigidly affixed thereto a second U shaped member 7 which together with a set screw 8 constitute a clamp adapted to embrace and be 35 secured to the free edge of a door 9. The screw 8 preferably carries an enlarged head 10 of a nature common in devices of this character to prevent marring the door. A metallic clamp 11 is secured to the front

40 transverse member 6^a of the clamp and comprises an upper horizontal wall 12, a horizontal wall 13, a front vertical wall 14 and rear vertical walls 15 and 16 which lie upon opposite sides of the wall 6^a and are rigidly secured thereto as by soldering or brazing. The walls 14 and 6^a have aligned openings 17 and 18 formed therein which openings are 45 adapted to receive either the shank 19 of a chalk holding clip 20, or the shank 21 of a pinning wire 22. A set screw 23 serves to bind either of these shanks against movement. The clip 20 is adapted to receive a tailor's chalk 20^a. The pinning wire 22 comprises a horizontal curved portion 24 50 which is connected by a vertical leg 25 with the shank 21. When it is desired to mark a

garment, as presently set forth, the chalk is used, while, when it is desired to form a hem upon a skirt the chalk holder is removed and the pinning wire is substituted there- 60 for, as illustrated in Fig. 3.

Assuming, for example, that it is desired to form the waist-line upon a garment the user secures the clamp to the free edge of a door at the height at which it is desired to 65 have the waist-line marked. Then, standing in such position that the chalk will contact with the goods to be marked and moving the door slowly back and forth, the user may, by turning slowly around, cause the 70 waist-line to be accurately marked entirely around the garment and this without aid from any other person.

While the marker is highly useful to 75 mark waistlines, it is equally useful in many other relations, such, for example, as marking the position of a yoke edge, the length of sleeves, places for pockets, folds, all sorts of trimming, hems of skirts, tucks, ruffles, etc. Furthermore, work of this nature may 80 be done without the assistance of a fitter and without a tape measure. A further feature of importance is that this marker is as well adapted for use in marking children's 85 garments as in marking the garments of adults.

In using the skirt gage as illustrated in Fig. 3, the person wearing the skirt to be hemmed stands inside of the curve of the pinning wire permitting the skirt to fall 90 over the pinning wire. The fitter then folds the material inwardly and upwardly and secures it about the pinning wire with pins. The person wearing the skirt turns slowly 95 from time to time and the formed hem is slipped from the free end of the pinning wire, while fresh material moves into position to be formed into a hem. During this operation the material, which has not yet been turned upwardly, falls freely into the 100 depression provided by the vertical leg 25. Thus, this material is not crowded and crumpled but lies freely and naturally, so as not to interfere with the fitter in properly forming the hem. By the use of this device, 105 flimsy materials such as crêpe de chines, Georgette crêpes and all soft silks may be accurately brought into hem formation, so that the skirt when completed will lie at 110 exactly the same distance from the floor all around.

It is to be understood that the invention

is not limited to the precise construction set forth but that it includes within its purview whatever changes fairly come within either the terms or the spirit of the appended 5 claims.

Having described my invention, what I claim is:

1. A device of the character described comprising a clamping element adapted to be secured to the free edge of a door and a chalk marker and a pinning wire interchangeably supported therefrom.
2. A device of the character described comprising a U shaped element and a set screw carried thereby to constitute a clamp adapted to be secured to the free edge of a door, of a perforate element carried by said clamp and a set screw carried by said perforate element and a pinning wire and a chalk-holder, each having a shank adapted to enter the perforation of the perforate element and be clamped therein by said set screw.
3. A device of the character described comprising a clamping element adapted to be secured to the free edge of a door, a second clamping element carried by the first

named clamping element and comprising a perforate member and a set screw and a chalk-holder comprising a shank adapted to pass through the perforations of said perforate member and be secured therein by said set screw.

4. A structure as recited in claim 3 in combination with a pinning wire having a shank that is likewise adapted to pass through the perforation of the perforate member and be secured therein by said set screw.

5. A device of the character described comprising a clamp adapted to be secured to the free edge of a door, a second clamp carried by the first named clamp and comprising a perforate member and a set screw and a pinning wire comprising a shank adapted to pass through the said perforate member and be engaged by said set screw, a vertical leg extending from said shank and a horizontal curved portion extending from the vertical leg.

In testimony whereof I hereunto affix my signature.

ELIZABETH THORPE.
